COMBINED COMPUTER CONTROL PANEL AND STAND

Jay Sucre, Newport, Minn., assignor to Sperry Rand Corporation, New York, N.Y., a corporation of Delaware

Original design application Apr. 26, 1961, Ser. No. 64,906. Divided and this application Apr. 2, 1962, Ser. No. 69,545

Term of patent 14 years

(Cl. D26—5)

Fig. 1

Fig. 2

Fig. 3

Fig. 4

FIGURE 1 is a perspective view of a combined computer control panel and stand showing my new design:

FIGURE 2 is a top plan view thereof;

FIGURE 3 is a side elevational view; and

FIGURE 4 is a back view.

The essential features of the design reside in the portions shown in full lines.

This application is a division of the copending application, Serial No. D. 64,906, filed April 26, 1961.

I claim:

The ornamental design for a combined computer control panel and stand, substantially as shown and described.
